C. BOOZE.
WALL PAPER.

No. 20,327.

Patented Nov. 18, 1890

UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 20,827, dated November 18, 1890.

Application filed September 27, 1890. Serial No. 366,385. Term of patent 3½ years.

To all whom it may concern:

Be it known that I, CHARLES BOOZE, a citizen of the United States, residing at Buffalo, in the county of Erie and State of New York,

5 have invented and produced a new and original Design for Wall-Paper, of which the following is a specification, reference being had to the accompanying photograph, forming part thereof.

10 The leading feature of my design consists of a cluster of flowers and leaves of pinks supported by a trellis or lattice-work of light lines to form a background, as represented in the accompanying photograph. The clusters are arranged vertically and placed at regular 15 distances apart upon tinted paper of any desired color.

What I claim is—

The design for wall-paper herein shown and 20 described.

Witness my hand this 13th day of September, 1890.

CHARLES BOOZE.
